ADVERTISING SIGN

Jack L. Steppe, 975 N. Center, Orange, Calif.

Filed June 20, 1963, Ser. No. 75,439

Term of patent 14 years

(Cl. D1—12)

I claim:
The ornamental design for an advertising sign, substantially as shown and described.
